Primary Examiner — Lauren R Calve

(74) Attorney, Agent, or Firm — Flynn Thiel, P.C.

(57) **CLAIM**

The ornamental design for a packaging bottle for liquids, as shown and described.

DESCRIPTION

FIG. 1 is a perspective view of a packaging bottle for liquids showing our new design;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

The broken lines illustrating portions of the packaging bottle for liquids are for environmental purposes only and form no part of the claimed design.

1 Claim, 6 Drawing Sheets
